UNITED STATES PATENT OFFICE.

WALTER C. ELZE, OF FOREST HILLS, NEW YORK, ASSIGNOR TO HAUCK MANUFACTURING COMPANY, OF BROOKLYN, NEW YORK, A CORPORATION OF NEW YORK.

PORTABLE ELONGATED BURNER APPARATUS.

Application filed July 28, 1927. Serial No. 208,944.

The invention relates to a novel burner member which is adapted for various purposes and designed to burn low grade liquid fuels such as kerosene or gasoline, furnace oil, etc.

The invention has for its object to provide apparatus of this character which shall have ample capacity to be suitable for use over extended periods of time but which will 10 shall be readily manipulated and not of undue weight or bulk. A further object of the invention resides in the novel combination of burner, reservoir and means for providing suitable pressure upon the combustible liquid, all being so devised and arranged as not to interfere with the ready manipulation of the apparatus which may be employed for such purposes as the destruction 15 of vermin in and disinfection of fox pens and runs, hen houses, dog kennels, etc.; also, as a substitute for spraying operations in the destruction of insect pests, scale, lice, and the like; also, in the bonding of rails with alloys, the lighting of street lamps; 20 and, particularly, as a ready means for the setting of back fires in the fighting of brush and forest fires. In the use of apparatus for purposes such as hereinbefore noted, it has been the practice generally to connect 25 a nozzle or like member with a source of fuel supply, under pressure, by means of a hose of more or less length which not only makes for a cumbersome and awkward apparatus but in certain instances interferes 30 with the free use of the burner. Other apparatus has been devised, also, with the nozzle rigidly connected to a tank, which, however, does not permit of the application 35 of flame at an appreciable distance from the operator, nor its application to otherwise 40 more or less inaccessible locations.

To this end, the novel apparatus is constructed as a unitary elongated member of appreciable length and provided with pressure producing means, the same affording a 45 readily portable device of ample capacity for use over extended periods of time.

The nature of the invention, however, will best be understood when described in connection with the accompanying drawings, in which:

Fig. 1 is a side elevation of the novel burner apparatus.

Fig. 2 is a plan thereof.

Fig. 3 is a front view.

Fig. 4 is a transverse vertical section taken on the line 4—4, Fig. 1, and looking in the direction of the arrows.

Fig. 5 is an enlarged fragmentary section of the pump end of the burner apparatus. 60

Fig. 6 is a fragmentary view, partly in section, and illustrates a modification.

Referring to the drawings, 10 designates a nozzle member or head of any well-known or special construction and adapted for the 65 combustion therein of a combustible liquid, preferably kerosene or gasoline—both being generally available, and whereby an extremely high temperature is attainable when operated under compressed air supplied thereto as hereinafter set forth. Temperatures as high as 1800° F. have been attained with the novel apparatus, making the same 70 adaptable for a great variety of purposes and providing a very effective instrument. 75 It will be understood, of course, that more than one nozzle may be utilized in the novel apparatus; but as a rule a single nozzle will be ample.

The nozzle 10 is carried at the forward end 80 of a rigid container member 11 for the combustible liquid and provided with an outlet opening 12 adapted to communicate with the said nozzle; and the said container is in the nature of an extended or elongated body 85 portion of cylindrical or, preferably, elliptical cross-section, being as a rule not less than three feet in length and, in some instances, ten or more times this length so as to afford long reach as well as ample fuel 90 capacity. Furthermore, the greater the exterior surface of the container, the more radiation is had therefrom to prevent undue warmth of same resulting from the heat generated at the nozzle, which, moreover, is displaced an appreciable distance from said container portion through the medium of an intermediate connecting pipe 13 which serves 95 also to supply the liquid fuel from said container to the nozzle. A valve 14 is included in said connection for controlling the flow of the combustible liquid from said container to regulate the flame developed by the nozzle as well as to entirely shut off the same when the apparatus is not in use. It is preferred, 100 also, to provide suitable guard means, as, for example, the metal strip 15 secured between the upper surface of the container and the top of the nozzle, to protect projecting parts 105 at the nozzle end of said apparatus as in 110

Fig. 1 is a side elevation of the novel burner apparatus.

carrying the same about. Furthermore, at the under side of the nozzle there is attached an ignition pan 16, and the nozzle, also, is provided with a clean-out plug 17.

It will be appreciated, moreover, that it is desirable to prevent said container member from becoming unduly heated as it is to serve as the handle or manipulating portion of the apparatus, being for this purpose preferably also of the elliptical cross-section, as shown, as well as to afford greater strength, especially in connection with apparatus of extreme length. The novel arrangement results, also, in a better distribution of weight, so that the burner is readily manipulated by a single operator even with containers of considerable length.

At the inner end of the body portion is removably secured a pump head 20 which constitutes also a filling cap for the container to permit, when removed, of access to the interior of the same as for filling and other purposes. This head, which is internally threaded and arranged to screw onto the externally threaded hollow block 21 welded to the end of the container, includes a cylindrical portion 22 sweated thereto and adapted to fit within the outer end of the said container. There is mounted for reciprocation in said cylinder, also, a piston member 23 whereby air under pressure may be introduced into the interior of the container as through the check valve 24 at the bottom of said cylinder. A handle 25 is provided for the piston 23 and projects exteriorly of the head for manually operating said piston to build up the desired pressure in the container. It will thus be observed that the burner apparatus hereinbefore described is complete in itself, readily portable and easily manipulated; and may, especially in the case of back-firing operations, be stored away conveniently for emergency use. It is, furthermore, readily transportable to the field of action and operable over appreciable periods of time and permits of convenient access to locations otherwise not readily accessible.

If the apparatus is to be utilized in a more or less vertical position, it will be appreciated that the inlet pipe 13 should be extended further into the container than ordinarily and as shown in Fig. 1, for example, approximately to the pump portion thereof, as indicated more clearly by the pipe 26, Fig. 6 of the drawings.

Provision is made, also, for supporting, and for conveniently suspending the novel burner apparatus when not in use, in the foot or like device 27 near the pump end, which with the pan 16 at the nozzle end and of somewhat shorter length will allow of temporarily leaving the apparatus unattended though operative; and the then slightly depressed forward or nozzle end will cause the same to continue in operation with only a small amount of fuel in the container. The foot member 27, furthermore, serves as a guard for protecting a pressure release plug or valve 28, secured to the underside of the container and extending within the guard, and designed to discharge the air under pressure from the container when the apparatus is not in commission.

I claim:

A unitary portable burner apparatus, comprising an elongated container affording a manipulating portion and a reservoir for combustible liquid, a removable pump and filling head closing the container at the one end and having means projecting exteriorly therefrom for operating the pump to develop pressure upon the liquid within the reservoir, which is provided at its opposite end with an outlet, a burner nozzle secured to said opposite end and communicating through said outlet with the reservoir, a valve controlling the said communication, supporting means secured to the under-side of the container, and a pressure release valve for the container and surrounded by the said supporting means.

In testimony whereof I affix my signature.

WALTER C. ELZE.
